UNITED STATES PATENT OFFICE.

THOMAS RAE, OF NEW CANAAN, CONNECTICUT.

DESIGN FOR A METAL BRACKET.

SPECIFICATION forming part of Design No. 25,586, dated June 2, 1896.

Application filed April 27, 1896. Serial No. 589,319. Term of patent 7 years.

To all whom it may concern:

Be it known that I, THOMAS RAE, a citizen of the United States, residing at New Canaan, in the county of Fairfield and State of Connecticut, have invented a new Design for a Metal Bracket, of which the following is a specification.

This bracket is adapted to connect parts of furniture or to support shelves.

10 The leading feature of this design for a bracket consists in the curved configuration and the circular bend at one end and helical groove at the other end.

15 In the drawings, Figure 1 is a side view, and Fig. 2 is a plan.

The portion *a* is approximately a quarter-circle bend. The eye *b* is circular and approximately parallel with the other end of the bracket, and this end is grooved helically at *c*. 20

I claim—

The design for a metal bracket, substantially as shown and described.

Signed by me this 22d day of April, 1896.

THOMAS RAE.
